GOOGLES

Joseph W. Aspenleiter, Rochester, N. Y., assignor
to Bausch & Lomb Optical Company, Rochester, N. Y., a corporation of New York

Application November 23, 1936, Serial No. 112,241

2 Claims.

(Cl. 2-14)

The present invention relates to goggles or the like and more particularly to goggles of the folding type.

One of the objects of the present invention is to provide new and improved goggles which may be folded so as to occupy a relatively small space. A further object is to provide an improved type of adjustable goggle bridge. Another object is to provide an improved connecting means for the eye units of folding goggles. These and other objects and advantages reside in certain novel features of construction, arrangement and combination of parts as will hereinafter be more fully set forth and pointed out in the appended claims.

15 Referring to the drawing:

Fig. 1 is a front view of a pair of goggles embodying this invention.

Fig. 2 is a top view thereof with the goggles in operative position.

20 Fig. 3 is a top view thereof with the goggles in folded position.

Fig. 4 is an enlarged fragmentary view of the latching mechanism in latching position.

Fig. 5 is a view similar to Fig. 4 showing the 25 bridge in unlatched position.

One embodiment of this invention is illustrated in the drawing wherein 10 designates, generally, a pair of goggles having two eye cups 11 and 12 of rigid material such as metal or the like, in 30 which are mounted the lenses 13 and 14, respectively. These lenses 13 and 14 may be of either the corrective or the protective type. The rear surfaces of the eye cups 11 and 12 are curved and provided with cushioning pads 15 and 16, respectively, to fit against the face of the wearer as is well known in the art.

Two rods 17 and 18 are pivotally secured on the tops of the eye cups 11 and 12, respectively, by pins 19 and 20, respectively. These rods 17 and 18 are provided with series transverse notches 21 and 22, respectively, and a hollow tubular member 23 slidably receives the notched free ends of the rods 17 and 18. The rods 17 and 18 are secured in the member 23 by a resilient latching 45 element 24 having a bowed central portion. This latching element 24 has a fulcrum 25 and a hook or detent 27 on one end and a similar fulcrum 26 and hook or detent 28 on the other. The latching element 24 is secured to the tubular member 23 by means of two projections 29 and 30 which loosely encircle the element 24 at the fulcrum portions 25 and 26.

The hooks or detents 27 and 28 ordinarily engage in the notches 21 and 22, respectively, to hold 50 the rods 17 and 18 in the tubular member 23. As shown in Fig. 5, pressing the bowed portion of the latching element 24 toward the tubular mem-

ber 23 causes the hook or detent portions 27 and 28 to swing about the fulcrum portions 25 and 26 and release the rods 17 and 18. The notches 21 and 22 permit the latching of the arms 17 and 18 at different points and thus provide a variation 5 of spacing between the eye cups for different pupillary distances.

The outer walls of the eye cups 11 and 12 are provided with extensions 31 and 32, respectively, to which the temple connections 33 and 34 are pivotally secured. These temple connections 33 and 34 are provided with series of holes or depressions 35 and 36 and terminate with sleeves 37 and 38 in which the ear engaging members 39 and 40 are slidable. Projections 41 and 42 15 on the ear engaging members 39 and 40 engage in the holes or depressions 35 and 36 to determine the lengths of the temples.

The tops of the eye cups 11 and 12 are provided with projecting stops 43 and 44, respectively, 20 which engage the rods 17 and 18 to determine the open or operative position of the goggles as shown in Fig. 2. A second pair of stops 45 and 46 engage the rods 17 and 18 to determine the closed or inoperative position of the goggles as shown in 25 Fig. 3.

From the foregoing, it will be apparent that I am able to attain the objects of my invention and provide a pair of goggles having an adjustable bridge and which can be folded so as to occupy a 30 small space. Various modifications can, of course, be made without departing from the spirit of my invention or the scope of the appended claims.

I claim:

1. A device of the character described comprising two lens holding members, a rod extending from each member, said rods having a plurality of transverse notches, a hollow member for receiving the free ends of said rods, and latching means engaging said notches for adjustably locking said rods in said hollow member. 35

2. A device of the character described comprising two lens holding members, a rod extending from each member, said rods having a plurality of transverse notches, a hollow member for receiving the free ends of said rods, and latching means engaging said notches for adjustably locking said rods in said hollow member, said latching device comprising a resilient element bowed in the center and having a fulcrum portion and a hook portion at each end, means on said hollow member for slidably holding said element at said fulcrum portions so that said hook portions can engage in said notches. 45

JOSEPH W. ASPENLEITER.
